UNITED STATES PATENT OFFICE

ELIAS G. FATTA, OF AMSTERDAM, NEW YORK

KNITTING MACHINE ATTACHMENT

Application filed February 25, 1931. Serial No. 518,207.

This invention relates to a knitting machine attachment which is especially for use on circular hosiery knitting machines of the "Banner" type, such as the machine forming the subject matter of United States Patent No. 1,450,946, issued on April 10, 1931 to Augustin Gagne, and which are equipped with a drop stitch attachment, and the invention has for one of its important objects to provide, in 10 a manner as hereinafter set forth, an attachment for knitting machines which is actuated by said knitting machines and which is operatively connected to the drop stitch attachment for actuating the same in a manner to provide 15 a knitted fabric having one or more crochet stitches running longitudinally therein, thus materially adding to the attractiveness and desirability of the fabric.

Other objects of the invention are to provide 20 a knitting machine attachment of the character described which will be simple in construction, strong, durable, efficient and reliable in operation, which may be manufactured at low cost and installed for operation 25 on a conventional knitting machine without the necessity of materially altering said machine structurally.

All of the foregoing and still further objects and advantages of the invention will 30 become apparent from a study of the following specification, taken in connection with the accompanying drawings wherein like characters of reference designate corresponding parts throughout the several views, and 35 wherein:

Figure 1 is a perspective view showing an attachment in accordance with this invention mounted in position on a knitting machine, said knitting machine being shown in broken 40 lines.

Figure 2 is a view in perspective showing the device removed from the knitting machine.

Figures 3 to 8, inclusive, are views showing 45 different samples of work which may be produced through the medium of an attachment in accordance with this invention on a knitting machine.

Referring to the drawings in detail, it will 50 be seen that the reference numeral 1 designates an elongated, substantially cylindrical drum having a longitudinal socket 2 extending thereinto from one end thereof for the reception of the end portion of an oscillating shaft (not shown) of the knitting machine 55 which is indicated in broken lines in Figure 1 and designated by the reference numeral 3. The cylindrical drum 1 is disposed horizontally and projects laterally from one side of the knitting machine 3 in spaced relation beneath the levers 4 of the drop stitch attachment which is mounted on the knitting machine and which is designated generally by the reference numeral 5. A set screw 6 is threaded into said one end portion of the cylindrical drum 1 for engagement with the oscillating shaft of the knitting machine in a manner to rigidly secure the drum in position 60 thereon for oscillation therewith.

The outer portion of the cylindrical drum 1 is provided with a pair of spaced, parallel, diametrically extending openings 7 for the reception of one end portion of a pair of flexible cables 8 which are adapted to be wound and unwound on the drum 1 as said drum oscillates. Set screws 9 are threaded into the cylinder 1 and engaged with the cables 8 for securing said cables to the drum and preventing the withdrawal of said cables from the openings 7. The set screws 9 are, of course, threaded into threaded openings provided therefor in the cylinder 1. Said threaded openings being at right angles to the openings 7 and communicating with intermediate portions of the openings 7.

Lugs 10 are rigidly mounted by any suitable means, such as welding or soldering to the outer sides of the levers 4 of the drop stitch attachment 5, the lugs 10 projecting laterally from the levers 4 and being mounted on the end portions of said levers which are remote from the pattern cam of the knitting machine 3 which actuates the drop stitch attachment levers. The lugs 10 are provided with diametrically extending openings 100 for the reception of the other end portions of the flexible cables 8 and set screws 11 are threaded longitudinally into the free ends of the lugs 10 for engagement with the cables for securing said cables to the lugs and pre-

venting the withdrawal of the cables from the diametrically extending openings in the lugs. It will be seen that the cables 8 are attached to the lugs 10 and to the drum 1 in a manner to permit the tension of said cables to be expeditiously adjusted as desired.

- 5 Through the medium of the attachment constituting this invention when used with the drop stitch attachment of the knitting machine, work having any desired number of 10 crochet stitches therein may be produced, as exemplified in Figures 3 to 8, inclusive, of the drawings. When the drum 1 is oscillated by the shaft of the knitting machine upon 15 which said drum is mounted, the cables 8 are wound thereon and unwound therefrom to actuate the levers 4 of the drop stitch attachment 5 on the knitting machine, as will be obvious. The reference numeral 12 designates 20 the usual tubular fabric in Figures 3 to 8, inclusive, of the drawings, and 13 designates the ornamental stitches which are formed through the medium of the attachment constituting this invention.
- 25 It is believed that the many advantages of a knitting machine attachment in accordance with this invention will be readily understood, and although the preferred embodiment of the invention is as illustrated and described, it is to be understood that changes in the details of construction may be had which will fall within the scope of the invention as claimed.

What is claimed is:—

- 35 1. In an attachment of the character described, the combination with a circular knitting machine and a drop stitch attachment operatively mounted thereon, said drop stitch attachment including a pair of cam actuated 40 levers, of an oscillating drum mounted on the machine and operatively connected thereto for actuation thereby, and a pair of flexible cables anchored to the levers of the drop stitch attachment and connected to the drum for winding thereon and unwinding therefrom in a manner to actuate the levers.
- 45 2. In an attachment of the character described, the combination with a circular knitting machine having an oscillating shaft and a drop stitch attachment operatively mounted on the knitting machine and including a pair of cam actuated levers, of a drum fixed on the oscillating shaft for movement therewith, and a pair of flexible cables anchored to the 50 levers of the drop stitch attachment and connected to the drum for winding thereon and unwinding therefrom in a manner to actuate the levers.
- 55 3. In an attachment of the character described, the combination with a circular knitting machine including an oscillating shaft and a drop stitch attachment operatively mounted on the knitting machine and including a pair of cam actuated levers, of an oscillating drum having a socket in one

end portion for the reception of the oscillating shaft, a set screw threaded into the drum and engaged with the oscillating shaft for locking the drum thereto for oscillation therewith, a pair of flexible cables anchored 7 to the levers of the drop stitch attachment and connected to the drum for winding thereon and unwinding therefrom for actuating said levers upon oscillation of the drum.

4. In an attachment of the character described, the combination with a circular knitting machine including an oscillating shaft and a drop stitch attachment operatively mounted on the knitting machine and including a pair of cam actuated levers, of an oscillating drum having a socket in one end portion for the reception of the oscillating shaft, a set screw threaded into the drum and engaged with the oscillating shaft for locking the drum thereto for oscillation therewith, a pair of flexible cables anchored 8 to the levers of the drop stitch attachment and connected to the drum for winding thereon and unwinding therefrom for actuating said levers upon oscillation of the drum, said 9 drum being provided with a pair of diametrically extending openings for the reception of the cables, and set screws threaded into the drum and engaged with the cables in the diametrically extending openings for detachably clamping said cables in the openings.

5. In an attachment of the character described, the combination with a circular knitting machine having an oscillating shaft and a drop stitch attachment operatively 10 mounted on the knitting machine and including a pair of cam actuated levers, of a horizontally disposed, substantially cylindrical drum having a longitudinal socket in one end portion thereof for the reception of an end portion of the oscillating shaft, a set screw threaded into the drum and engageable with the oscillating shaft in a manner to secure the drum thereon for oscillation therewith, said drum being further provided with a pair of 11 spaced, parallel, diametrically extending openings, lugs rigidly mounted on the levers of the drop stitch attachment and having diametrically extending openings therein, flexible cables extending through the openings 1 in the lugs and in the drum, and set screws threaded into the lugs and the drum and engaged with the cables for securing said cables to the lugs and the drum, said cables constituting means for operatively connecting the 1 levers of the drop stitch attachment to the drum for actuation by said drum.

6. In an attachment of the character described, the combination with a circular knitting machine having an oscillating shaft and a drop stitch attachment operatively 1 mounted on the knitting machine and including a pair of cam actuated levers, of a horizontally disposed, substantially cylindrical drum having a centrally disposed, longitudi-

nally extending socket in one end portion thereof for the reception of the oscillating shaft, a set screw threaded transversely into said one end portion of the drum for engagement with the oscillating shaft in a manner to secure the drum thereon for oscillation therewith, the drum being further provided with a pair of spaced, parallel, diametrically extending openings, a pair of substantially cylindrical lugs rigidly mounted on the levers of the drop stitch attachment and projecting laterally therefrom, said lugs being provided with diametrically extending openings, a pair of flexible cables having one end portion disposed through the openings in the lugs and their other end portions disposed through the openings in the drum, set screws threaded transversely into the drum substantially at right angles to the openings therein and engaged with the cables for clamping said cables in the openings in the drum, and set screws threaded longitudinally into the free ends of the lugs and engaged with the cables in a manner to clamp said cables in the lug openings, the cables providing means for operatively connecting the levers of the drop stitch attachment to the drum for actuation by said drum.

7. In combination with a circular knitting machine and a drop stitch attachment operatively mounted thereon, an oscillating drum, and means windable on the drum and operatively connected to the drop stitch attachment for actuating same.

8. In combination with a circular knitting machine and a drop stitch attachment operatively mounted thereon, an oscillating drum operatively connected to the machine for actuation thereby, and flexible means windable on the drum and operatively connected to the attachment for actuating same.

In testimony whereof I affix my signature.
ELIAS G. FATTA.
